UNITED STATES PATENT OFFICE.

JOHN SULLIVAN, OF WASHINGTON, DISTRICT OF COLUMBIA, ASSIGNOR TO JOHN T. McNICHOLAS, OF NEW YORK, N. Y.

DESIGN FOR A BADGE.

No. 40,029.

Specification for Design.

Patented June 8, 1909.

Application filed April 2, 1909. Serial No. 487,595. Term of patent 14 years.

To all whom it may concern:

Be it known that I, JOHN SULLIVAN, a citizen of the United States, residing at Washington, District of Columbia, have invented a new, original, and ornamental Design for Badges, of which the following is a specification, reference being had to the accompanying drawing, forming part thereof.

The figure is an enlarged plan view of a badge showing my design, the same consisting of a profile of the head of a child upon a circular back-ground having radial arms, a symbol or character below and to the left of the chin of the child and the letters H N S above the head thereof.

I claim—

The ornamental design for a badge, as shown and described.

JOHN SULLIVAN.
